Primary Examiner — Michael A Pratt(74) *Attorney, Agent, or Firm* — QuickPatents; Kevin Prince(57) **CLAIM**

I claim the ornamental design for a trailer hitch cover, as shown and described.

DESCRIPTION

FIG. 1 is a front perspective view of a first embodiment of a trailer hitch cover, showing my new design;

FIG. 2 is a rear perspective view of FIG. 1;

FIG. 3 is a right-side elevational view of FIG. 1, the left-side elevational view being a mirror image thereof;

FIG. 4 is a top plan view of FIG. 1, the bottom plan view being a mirror image thereof;

FIG. 5 is a front elevational view of FIG. 1;

FIG. 6 is a rear elevational view of FIG. 1;

FIG. 7 is a front perspective view of a second embodiment thereof;

FIG. 8 is a rear perspective view of FIG. 7;

FIG. 9 is a right-side elevational view of FIG. 7, the left-side elevational view being a mirror image thereof;

FIG. 10 is a top plan view of FIG. 7, the bottom plan view being a mirror image thereof;

FIG. 11 is a front elevational view of FIG. 7; and,

FIG. 12 is a rear elevational view of FIG. 7.
